UNITED STATES PATENT OFFICE.

AARON J. MARTIN, OF CANTON, OHIO.

BOTTLE-CAP.

SPECIFICATION forming part of Letters Patent No. 736,988, dated August 25, 1903.

Application filed January 9, 1903. Serial No. 138,350. (No model.)

To all whom it may concern:

Be it known that I, AARON J. MARTIN, a citizen of the United States, residing at Canton, in the county of Stark and State of Ohio, have 5 invented certain new and useful Improvements in Bottle-Caps; and I do hereby declare that the following is a full, clear, and exact description of the same, reference being had to the annexed drawings, making a part of 10 this specification, and to the figures of reference marked thereon, in which—

Figure 1 is a view of the cap, showing its position before folded and connected to the bottle. Fig. 2 is a view showing the disk portion of the cap properly connected to the head of the bottle and illustrating the attaching-strip extended. Fig. 3 is a vertical section of the cap, showing the same properly connected. Fig. 4 is a view showing the cap 20 properly connected to a bottle.

The present invention has relation to bottle-caps; and it consists in the novel construction hereinafter described, and particularly pointed out in the claims.

25 Similar numerals of reference indicate corresponding parts in all the figures of the drawings.

In the accompanying drawings, 1 represents the cap-disk, which is preferably formed circular and of a size to permit the same to be placed over the head and cork of a bottle and folded under the bead, substantially as illustrated in Fig. 2.

From the disk 1 extends the short neck 2, 35 to which neck is joined the rectangular portion 3, said rectangular portion being of a length sufficient to be wrapped around the neck of a bottle below the bead thereof, and for the purpose of properly connecting said 40 rectangular strip when brought into the position illustrated in Fig. 4 one face of said strip is provided with some suitable adhesive substance, so that when the same is moistened it will properly hold said rectangular strip 3 in 45 proper position and bind the portion of the disk 1 over which said strip is wrapped.

It will be understood that when the disk 1 is brought into the position illustrated in Fig. 2 folds will be formed; but after the rectangular strip 3 has been properly wound 50 around said folds they will be covered, thereby furnishing a finished appearance to the cap.

It will be understood that by my peculiar arrangement advertising matter can be 55 placed upon the rectangular strip 3 at such a place that when it is properly wrapped it will be exposed to view and at the same time present a pleasing appearance owing to the neat finish of the cap proper.

60 It will be understood that the material used for the above-described cap should be such that it can be easily attached to the bottle and at the same time has sufficient strength to remain in fixed position at all times and under 65 all circumstances.

Having fully described my invention, what I claim as new, and desire to secure by Letters Patent, is—

1. A bottle-cap consisting of a disk adapted 70 to be folded upon the neck of the bottle and provided with a rectangular strip, said rectangular strip adapted to be folded around the neck of a bottle and over the folded portion of the disk, substantially as and for the 75 purpose specified.

2. The herein-described bottle-cap consisting of a disk, a rectangular strip spaced from said disk and connected thereto, one face of said strip provided with an adhesive substance, substantially as and for the purpose 80 specified.

In testimony that I claim the above I have hereunto subscribed my name in the presence of two witnesses.

AARON J. MARTIN.
